ELECTRIC WAVE AMPLIFIER

Michael J. Burger, South Ozone Park, N. Y., assignor to Western Electric Company, Incorporated, a corporation of New York

Application December 4, 1940, Serial No. 368,416

3 Claims. (Cl. 179—171)

The invention relates to electric wave amplifiers and in particular to the operation of such amplifiers so as to reduce or eliminate undesired frequency components in the output current.

An object of the invention is to secure efficient amplification of applied waves while reducing or suppressing in the output current the even order distortion products. A feature of the invention is the generation in one element of the amplifier of even order distortion products of such magnitude and phase relationship that they substantially neutralize even order distortion products produced in another element of the amplifier.

The invention is applicable to electric wave amplifiers for any purpose, but is particularly advantageous in amplifiers for waves in the audio frequency range so that, by the neutralization of the harmonic distortion, the reproduced audio frequency currents are free from distortion.

The invention may conveniently be embodied in the known amplifier system comprising a driver amplifier, and a phase inverter amplifier, jointly controlling two amplifiers connected in push-pull or opposed relationship though it is not limited to this particular use. In accordance with the present invention, the circuit elements associated with the inverter amplifier are so proportioned that the even order distortion products generated in the inverter amplifier are of such magnitude and phase as to neutralize in the input of the push-pull amplifier the even order distortion products produced by the driver amplifier.

A more complete understanding of the invention may be had from the following detailed description, together with the attached drawing which is a schematic circuit diagram of a typical embodiment of the invention.

Electric waves from any desired source are applied to the input terminals 1, 2 of the amplifier, transmitted through the capacitor 3, and produce a voltage across the resistor 4 connected across the input circuit of the driver amplifier 5. The output of the driver amplifier 5 produces a voltage across the resistor 6 which is applied through the capacitor 7 to produce a voltage across the resistors 8 and 9 connected in serial relationship across the input circuit of the amplifier 10, forming one side of a push-pull amplifying arrangement. The voltage developed across the resistor 9 is also supplied to the input circuit of the inverter amplifier 11. The output of the inverter amplifier 11 produces a voltage across the resistor 12, which is applied through the capacitor 13

to produce a voltage across the resistor 14 connected across the input circuit of the amplifier 15 forming the other side of the push-pull combination. The outputs of the push-pull amplifiers 10 and 15 are supplied in the usual manner to separate primary windings of the transformer 16, and thence through transformer 16 to the output circuit. The driver amplifier 5 may be self-biased by the usual cathode resistor 17, and similarly the inverter amplifier 11 may be self-biased by the cathode resistor 18. The cathode bias resistors may be shunted by the usual bypass condensers. Power from any suitable sources is supplied to the cathodes and anodes of the various amplifiers in the usual manner.

Assume that an electric wave of fundamental frequency $+F$ is applied to the input circuit of the driver amplifier 5 of sufficient magnitude to heavily load the driver amplifier. The output circuit of the driver amplifier 5 will then contain the fundamental frequency $-F$ and the even order distortion products, which may be represented by $+F2$, and these are applied to the input circuit of the push-pull amplifier 10. A portion of the output of the driver amplifier $-F$ and $+F2$ is also supplied to the input circuit of the inverter amplifier 11. In accordance with the present invention the circuit elements associated with the inverter amplifier 11 are so proportioned that the inverter amplifier 11 produces a second order distortion product which has twice the amplitude of the second order distortion product produced by the driver amplifier 5, and an amplification such that the output at the fundamental will be equal in magnitude to the output of the driver stage. The output of the inverter amplifier 11 will comprise the input inverted in phase and the generated second order distortion products, and will thus comprise $+2F2$, $-F2$ and $+F2$, which is equal to $+F+F2$. The output of the inverter amplifier 11 will be $+F+F2$, whereas, the output of the driver amplifier 5 will be $-F+F2$. In accordance with the well-known operation of push-pull circuits, the fundamental frequency $-F$ supplied to the input circuit of the amplifier 10 and the fundamental frequency $+F$ supplied to the input circuit of the amplifier 15 will be combined in the primary windings of the transformer 16 and supplied through the transformer 16 to any desired load or utilization circuit. On the other hand, the second order distortion product in the output of the driver amplifier 5 and the similar second order distortion product in the output of the inverter amplifier 11 will mutually neutralize each other in the input

circuit of the push-pull amplifying stage and these products will not be present in the output supplied to the load.

The driver amplifier and the inverter amplifier may be vacuum tubes of the same or different types. From the manufacturer's data on the type of vacuum tube selected, the grid bias and anode voltages for the driver amplifier are selected so that when the driver amplifier is fully loaded the output voltage applied to the amplifier 10 will load the amplifier 10 to a desired maximum value. Under these conditions, the driver amplifier 5 will have a known impedance between anode and cathode and should operate into an output circuit having a preferred value of alternating current impedance which is determined largely by the voltages selected. The even order harmonic distortion products which are largely made up of the second and higher even harmonics of the fundamental frequencies under these conditions may then be determined from the manufacturer's data or by actual measurements. Grid bias and anode voltages are then selected for the inverter amplifier 11 such that when this amplifier is working into a selected value of alternating current load impedance, the output of even order distortion products will be 6 decibels greater than the output of even order distortion products from the driver amplifier 5. The relative values of the resistors 8 and 9 are then selected so that the output voltage from the inverter amplifier 11 applied to the push-pull amplifier 15 will be equal to the output voltage from the driver amplifier 5 applied to the push-pull amplifier 10.

In a practical embodiment of the invention, the driver amplifier 5 and the inverter amplifier 11 were Western Electric 262-B vacuum tubes and the amplifiers 10 and 15 were Western Electric 300-A vacuum tubes. The resistor 6 was 150,000 ohms, the resistor 8 was 400,000 and the resistor 9 was 40,000 ohms, the biasing resistor 17 being 7,500 ohms. The resistor 12 was 125,000 ohms, the resistor 14 was 300,000 ohms, while the biasing resistor 18 was 6,500 ohms. Neglecting the coupling capacitors 7 and 13, and assuming input impedance of the amplifiers 10 and 15 to be infinite, the driver amplifier 5 was working into an alternating current load of some 112,000 ohms whereas the inverter amplifiers 11 was working into an alternating current load impedance of some 88,000 ohms. It should be noted that in order to maintain the proper phase inversion relationship that capacitor 13 must be made considerably larger than capacitor 7. In 55 this typical embodiment C13 was .25 microfarad

whereas C7 was .1 microfarad. Under these conditions, the even order distortion products in the output of the push-pull amplifier were reduced some 20 decibels below the value that these products would have if the driver amplifier 5 and the inverter amplifier 11 were operating under the same conditions, and were respectively associated with circuit elements of the same magnitude.

What is claimed is:

1. A push-pull amplifier, a driver amplifier for supplying oscillations to one side of said push-pull amplifier and having circuit elements of such constants as to produce a definite ratio of even order distortion products to the fundamental of the applied oscillations, an inverter amplifier having an input connected to the output of said driver amplifier and an output connected to the other side of said push-pull amplifier and having circuit elements of such constants as to produce even order distortion products of the applied oscillations of such magnitude and phase as to substantially neutralize the even order distortion products supplied by said driver amplifier to said push-pull amplifier.

2. A resistance-capacitance coupled amplifier comprising a driver amplifier, an inverter amplifier, and two amplifiers in push-pull relationship, characterized by the circuit elements associated with the inverter amplifier being so proportioned that the inverter amplifier produces even order distortion products of the applied signal having twice the amplitude of the even order distortion products produced by the driver tube, whereby the even order distortion products supplied by the inverter amplifier to the push-pull amplifiers substantially cancel the even order distortion products supplied by the driver amplifier to said push-pull amplifiers.

3. In combination, a load circuit, a first amplifier for supplying oscillations to said load circuit having circuit elements of such constants as to produce a definite ratio of even order distortion products to the fundamental frequency of the applied oscillations, and a second amplifier having an input coupled to the output of said first amplifier for supplying oscillations equal in magnitude and opposed in phase to the oscillation from said first amplifier to said load circuit, having circuit elements of such constants as to produce even order distortion products of the fundamental frequency of the applied oscillations of such magnitude and phase as to substantially neutralize the even order distortion products supplied by said first amplifier to said load circuit.
